UNITED STATES PATENT OFFICE.

ERNEST A. EULER, OF BLAIR, KANSAS.

TITLE.

1,063,865.

Specification of Letters Patent.

Patented June 3, 1913.

Application filed August 3, 1912. Serial No. 713,087.

To all whom it may concern:

Be it known that I, ERNEST A. EULER, a citizen of the United States, residing at Blair, in the county of Doniphan and State 5 of Kansas, have invented new and useful Improvement in Tiles, of which the following is a specification.

This invention relates to tiles, and particularly to reinforcing means therefor.

10 The object of the invention is to provide a reinforcing means which will strengthen the tile to a maximum degree, and which permits of the coupling together of the reinforcing elements of adjoining tiles, so that 15 the tiles will neutrally reinforce each other.

The invention consists of the features of construction, combination and arrangement of parts hereinafter fully described and claimed, reference being had to the accompanying drawings, in which:

Figure 1 is a perspective view of a tile provided with my improved reinforcing and coupling means. Fig. 2 is a longitudinal section in perspective of the same. Fig. 3 is 25 a horizontal transverse section through the tile. Fig. 4 is a detail section illustrating the manner of coupling adjoining tiles. Fig. 5 is a detail view of one of the short supplemental reinforcing and coupling elements.

30 Referring to the drawing, 1 designates a cylindrical tile formed of cement, clay or other plastic material. Embedded in this tile at fixed intervals around the same are reinforcing and coupling elements 2, each 35 preferably formed of a single piece of wire. Each coupling element 2 is substantially V-shaped and its arms 3 and 4 are connected at their converging ends by an elongated loop 5, while the free ends of said arms terminate in hooks 6 having anchoring extensions 7.

The series of reinforcing and coupling elements 2 are arranged in zigzag relation, or so that their arms cross each other, the 45 arm 3 of one element crossing the adjacent arm 4 of the other element at one side, thereof, while the arm 4 of the element in question crosses the arm 3 of the next adjacent element at the opposite side thereof. 50 By this arrangement the tile is reinforced by a trusswork series of wires, which materially increase its strength and resistance to fracture.

The looped ends 5 project beyond one of 55 the end edges 8 of the tile, while the opposite end edge of the tile is provided with slots 10

and transverse openings 11. The hooked ends 6 of the arms of adjacent reinforcing elements are arranged in lapping relation or in alinement, and slightly spaced apart, and the complementary pairs or sets of hooks terminate adjacent to the slots 10 and with their bight portions in transverse alinement with the openings 11, the hooks of each pair being arranged on opposite sides of the line of the adjacent slot or recess 10.

The construction described, in addition to providing reinforcement of maximum strength, also adapts adjoining tiles of a conduit to be easily and conveniently coupled together. It will be apparent that the loops 5 projecting from the end 8 of one tile may be seated in the slots or recesses at the end 9 of an adjacent tile, so as to come between the pairs of coupling hooks 6 of the latter named tile, whereby upon the passage of pins 12 through the openings 11 the tiles may be coupled together. These pins or plugs 12 may be cemented or otherwise suitably secured in place, when it is not desired to provide for the disconnection of the tiles. It will, of course, be apparent that the ends 8 of one tile from which the loops 5 project may be coupled with the end 9 of a tile at the end thereof, while the end 9 of the same tile may be connected with the end 8 of another tile at the opposite end thereof, so that a series of tiles may be easily, conveniently and securely coupled together. Fig. 4 shows two adjacent tiles coupled and ready for the insertion of a fastening pin 12.

If desired, the end of the tile from which the loops 5 project may be provided with supplemental reinforcing and coupling elements 13, each comprising a single piece of wire bent to form a loop 14 and diverging arms 15. These elements 15 are equal in number to the coupling elements 2 and their loops 14 are arranged opposite and in parallel relation to the loops 5, the arms 15 and inner ends of said loops 14 being embedded in the tile. When two adjoining tiles are coupled together the loops 5 and 14 of one tile enter the recesses 10 of the adjoining tile and fit between and in alinement with the hooks 6 of the respective complementary pairs of hooks of the coupling elements. This construction affords a firm and secure coupling connection between adjoining ends of tiles, and at the same time provides for the strengthening of the tile ends against possibility of fracture.

I claim:—

A tile comprising a tubular body having an annular series of spaced recesses in one of its end edges and transverse openings adjacent to such end edge and in alignment with said recesses, and reinforcing elements embedded in said tile, said reinforcing elements comprising an annular series of independent V-shaped wires, said wires having 5 their diverging arms arranged in crossing relation throughout the series of wires, each wire having free hooked ends arranged in spaced and lapping relation to the similar

ends of adjacent wires, the hooked ends of the wires extending in pairs into said recesses, and in line with said transverse openings at one end of the tile, and the apex portions of the wires being formed with loops projecting beyond the opposite end of the tile. 15 20

In testimony whereof I affix my signature in presence of two witnesses.

ERNEST A. EULER.

Correction in Letters Patent No. 1,063,865.

It is hereby certified that the name of the patentee in Letters Patent No. 1,063,865, granted June 3, 1913, for an improvement in "Tiles," was erroneously written and printed "Ernest A. Euler," whereas said name should have been written and printed *Ernest H. Euler*; and that the proper corrections have been made in the files and records of the office and are hereby made in said Letters Patent.

Signed and sealed this 30th day of September, A. D., 1913.

[SEAL.]

R. T. FRAZIER,

Acting Commissioner of Patents.

I claim:—

A tile comprising a tubular body having an annular series of spaced recesses in one of its end edges and transverse openings adjacent to such end edge and in alignment with said recesses, and reinforcing elements embedded in said tile, said reinforcing elements comprising an annular series of independent V-shaped wires, said wires having 5 their diverging arms arranged in crossing relation throughout the series of wires, each wire having free hooked ends arranged in spaced and lapping relation to the similar

ends of adjacent wires, the hooked ends of the wires extending in pairs into said recesses, and in line with said transverse openings at one end of the tile, and the apex portions of the wires being formed with loops projecting beyond the opposite end of the tile. 15 20

In testimony whereof I affix my signature in presence of two witnesses.
